UNITED STATES PATENT OFFICE.

RALPH C. WEBSTER, OF HAVERHILL, MASSACHUSETTS.

CUSHIONED TOE REENFORCE FOR LASTS.

Application filed March 1, 1919. Serial No. 279,980.

To all whom it may concern:

Be it known that I, RALPH C. WEBSTER, a citizen of the United States, residing at Haverhill, in the county of Essex and State of Massachusetts, have invented new and useful Improvements in Cushioned Toe Re-enforces for Lasts, of which the following is a specification.

The present invention relates to lasts used in shoe making, particularly those which are sharply pointed at the toe, and has for its object to provide a cushioned reenforce at the toe in order to prevent breaking and splintering of the last at this point.

Lasts used in the building up of shoes are substantially all made of wood, and they are subject to much knocking about, both from careless handling, and dropping on benches and floors, etc., and to being hammered in the course of the lasting operation in order to make the upper smooth and to lay the sole. Particularly in making turned shoes having pointed toes, the toe, after turning of the shoe and reinsertion of the last, needs to be thus hammered, and rubbed under pressure, to smooth out wrinkles. Obviously the toe of such a last is particularly weak; but this is the part which receives most of the pounding in the normal course of shoe-making. It has also small strength to resist the shocks received when it is carelessly dropped on the floor point down, or carelessly thrown or dropped on a bench, or struck by other lasts carelessly handled. Thus it happens that in factories using pointed lasts, there is very high breakage, amounting approximately to 50% more or less of all the lasts in use, and consisting principally in snapping off or splintering of the pointed toes. My object has been to prevent this breakage; and I have accomplished this object by providing a reinforcing piece in the bottom of the last at the toe, made of material which is tough and strong, and by interposing between such reinforcing piece and the wood of the last, a cushion so disposed as to soften the effect of blows received upon the reenforce, and thus largely or wholly to prevent splintering of the wood by such blows.

Referring to the drawings in which a form of my invention is shown, Figure 1 is a side elevation of a pointed toe last, showing the toe end thereof in vertical longitudinal section, with the reenforce and cushion comprising the present invention applied

thereto; Figure 2 is a top plan, and Figure 2 a bottom plan view of the toe end of the last.

The same reference characters indicate the same parts in all the figures.

In embodying my invention in a last, a groove is cut in the bottom extending from the toe extremity rearward to a suitable distance, and so placed that the sides of the groove are approximately equally spaced at each side of the extreme point. The formation of the groove thus results in cutting away the extreme point of the last. In this groove then is laid a cushion strip *a*, and upon the cushion strip a reinforcing piece or reenforce *b*. These pieces are secured to the toe part *c* by any suitable means, such as wood screws *d* and *e* inserted through holes in the reenforce and screwed into the wooden last body. The reenforce extends at the forward end out as far as the original point of the last body, and it is finished to conform to the original outline and surface contours of the tip end or point of the last. The cushion piece, is likewise extended far enough so that it may be finished at the exposed end in conformity with the original contours.

The combined thickness of the reenforce and cushion is preferably equal to the depth of the groove in which they are laid, whereby the outer surface of the reenforce comes flush with the last bottom; and the individual thicknesses of these inserted pieces are fixed at the values which give sufficient strength in the reenforce and sufficient cushioning effect in the cushion. I will say for the benefit of those skilled in the art, but without intending thereby to indicate a limitation in the scope of the protection which I claim, that the reenforce may have a thickness of about $\frac{5}{32}$ of an inch and the cushion a thickness of about $\frac{3}{32}$ of an inch; their combined thickness being then about $\frac{1}{4}$ of an inch and the slot or groove containing them being correspondingly deep.

Various materials may be used for making these inserted pieces. I have used as the material for the reenforce, hard fiber of the sort now well known and widely used for bearings and washers in connection with machinery, and for electrical insulation; and for the cushion I have used a vulcanized rubber composition having substantially the degree of elasticity and firmness possessed by rubber heels of the best grades.

This kind of fiber has great strength and toughness, is not brittle nor is it easily chipped by knocking about and hammering of the last, it does not flow and take a permanent set under blows of the hammer, as soft metal does, and it is at the same time yielding enough so that it does not cut or deface the upper leather or the fabric lining when the shoe upper is hammered upon 5 in the course of either lasting a turned shoe or smoothing out the upper of such shoe after it has been turned, or in lasting any other sort of a shoe.

In the operation of lasting the sole is secured temporarily to the last bottom by a 10 number of tacks, one of which is driven near the toe and near the longitudinal center line of the last bottom; in other words in the part occupied by the reenforce. The 15 above described fiber which I prefer to use for the reenforce is so hard and tough that it will turn the points of most tacks driven into it, and is liable to be torn when a tack which has penetrated it is afterwards 20 drawn, wherefore I have provided an inserted plug *f* which is forced into a hole in the reenforce at the point where the toe tack for thus temporarily securing the sole 25 is ordinarily placed. I have used leather 30 as the material for this plug since leather is readily penetrable by a tack and it has such a closely knit fibrous structure that it is not injured by many times repeated insertions and removals of tack points. In 35 thus indicating the advantages of leather as the material for the tack-receiving insert, I do not restrict this feature of the invention to that specific material, but intend to protect an insert of any sort of material adapted to serve the purpose. Another 40 feature to which I direct attention is that the screw *d* is placed so near to the inserted plug that its head somewhat overlaps the rim of the plug and so prevents 45 the latter from dropping out of place. I may omit this feature without departure 50 from the main idea of the invention, and depend upon friction alone or adhesive to retain the plug in position; but the particular means above described, consisting of the

overlapping screw head is of value in some instances, and is here claimed.

What I claim and desire to secure by Letters Patent is:

1. A wooden last having applied to its 55 bottom a reinforcing piece of material tougher and more tenacious than wood extending lengthwise of the last body and its forward end providing the toe extremity of the last, and a cushion interposed between said piece and the last body.

2. A last having a groove or channel in its bottom extending longitudinally and including the center of the toe extremity, a cushion strip laid in said groove next to the last body, and a reinforcing strip laid upon said cushion strip, its outer surface being substantially flush with the bottom of the last, and its forward end forming the toe extremity.

3. A last comprising a wooden body having a narrow toe end, a reinforcing strip of material having greater tenacity than wood set into the bottom of the last and disposed to form the tip and sides adjacent 75 to the tip, of the toe extremity thereof, and a cushion interposed between said strip and the overlying last body.

4. The combination with a wooden last, of a hard fiber reenforce inlaid in the bottom between the sides of the last and forming the toe extremity thereof such reenforce being of less width than the toe part of the last back from said extremity and a cushion piece of vulcanized rubber composition interposed between the fiber reenforce and the wood of the last.

5. A last comprising a wooden body, a reinforce of a harder and more tenacious material than wood applied to the bottom 90 of said last and having a hole in it, a body of more readily penetrable material contained in said hole, and a headed fastener securing said reenforce to the last and arranged with its head overlapping the rim of 95 said inserted body.

In testimony whereof I have affixed my signature.

RALPH C. WEBSTER.
